UNITED STATES PATENT OFFICE.

ARTHUR LINDÉN AND PAUL HIERSEMANN, OF VESTERÅS, SWEDEN,
ASSIGNORS TO ALLMÄNNA SVENSKA ELEKTRISKA AKTIEBOLAGET, OF VESTERÅS, SWEDEN.

CURRENT-COLLECTOR.

No. 827,314.

Specification of Letters Patent.

Patented July 31, 1906.

Application filed October 18, 1905. Serial No. 283,271.

To all whom it may concern:

Be it known that we, ARTHUR LINDÉN, a subject of the King of Sweden, and PAUL HIERSEMANN, a subject of the King of Saxony, and residents of Vesterås, Sweden, have invented a new and useful Improvement in Current-Collectors for Electric Railways, of which the following is a specification, reference being had to the drawings accompanying and forming a part hereof.

This invention relates to overhead supply-conductors for electric railways, and especially such conductors which have automatically-turning-over contact-bows.

15 The object of the invention is to provide a supply-conductor of the said kind which will work in a reliable manner and can be used in railways where the height of the contact-wire over the ground varies considerably.

20 The invention consists, chiefly, in that the contact-bow is pivotally connected to the vertically-guided upper point of a rhomb-guide the lower rods of which are turnable on axles located at some distance from each 25 other and mechanically connected to each other, so that their turning in one and the same direction, and thereby the tilting of the guide in the one direction or the other, is prevented.

30 In the accompanying drawings we have illustrated a contact device embodying our invention.

Figure 1 is a side view of the supply-conductor, and Fig. 2 a front elevation of the 35 same.

The dotted lines 1 indicate the part of a car on which the contact device is provided. On the roof of the car are journaled an insulated axle 2, extending across the roof, and two 40 shorter axles 3 on each side of the lantern of the car. To the said axles 2 and 3 are pivotally connected rods 5, to the upper ends of which are hinged frames 6 and 7, pivotally connected to each other at their upper ends, 45 so that the said frames, together with the rods 5, constitute a rhomb-guide, the top or point of which is movable vertically or approximately vertically. At the said point the contact-bow proper, 8, is journaled, the

same being provided with downward-projecting parts 9, actuated by springs 10 and 11, which are secured to links 15 and 16 and tend to keep the contact-bow in a vertical position. The said links 15 and 16 are hinged to the frames 6 and 7 and to each other. 50

On account of the friction against the contact-wire 12 the contact-bow during the movement of the car will automatically be turned backward in relation to the direction of movement. (Indicated by the arrow in 60 Fig. 1.) If the direction of movement of the car be changed, the contact-bow will be automatically turned over in the opposite direction to that shown in the drawings, such turning over being accomplished without 65 difficulty on account of the small height of the contact-bow, which requires only a slight lifting of the contact-wire for allowing the contact-bow to turn over.

The rods 5 or their axles are actuated by 70 springs 13, tending to turn the said rods toward each other, so as to press with desired force the contact-bow upward. In order to prevent the rods 5 from being turned in one and the same direction, whereby the rhomb-guide would be tilted, the said rods or their 75 axles are mechanically connected to each other—for instance, by means of a chain 14 and chain-wheels or toothed segments or the like—compelling the said rods to turn in opposite directions.

Having now particularly described our invention, what we claim as new, and desire to secure by Letters Patent, is—

1. In an overhead supply-conductor for 85 electric railways the combination, of a contact-bow, a rhomb-guide to the top of which the said contact-bow is connected, links hinged to the said rhomb-guide and to each other, springs between the said links and the 90 said contact-bow and mechanical connections between the lower rods of the said rhomb-guide, substantially as and for the purpose set forth.

2. In an overhead supply-conductor for 95 electric railways the combination of axles disposed at some distance from each other, a rhomb-guide the lower rods of which are con-

nected to the said axles, mechanical connec-
tions between the said axles, a contact-bow
pivotally connected to the top of the said
rhomb-guide, links hinged to the latter and
S to each other, and springs between the said
links and the said contact-bow substantially
as and for the purpose set forth.

In testimony whereof we have signed our

names to this specification in the presence of
two subscribing witnesses.

ARTHUR LINDÉN.
PAUL HIERSEMANN.
